UNITED STATES PATENT OFFICE.

JACOB W. GERKE, EDWARD J. BRAISTED, AND EDMOND T. KELLEHER, OF FLUSHING,
NEW YORK; SAID GERKE ASSIGNOR TO SAID BRAISTED AND SAID KELLEHER.

VENTILATOR.

1,228,202.

Specification of Letters Patent.

Patented May 29, 1917.

Application filed April 13, 1916. Serial No. 90,869.

To all whom it may concern:

Be it known that we, JACOB W. GERKE, EDWARD J. BRAISTED, and EDMOND T. KELLEHER, citizens of the United States, residing at Flushing, in the county of Queens and State of New York, have invented certain new and useful Improvements in Ventilators, of which the following is a specification.

10 This invention relates to ventilators, and pertains especially to a ventilating device adapted to be applied to cars, automobiles, buildings, windows, and in various places for exhaust ventilation.

15 The object of the invention is to provide a mechanically operated ventilator vane or valve contained within an open end casing forming a throat and coöperating with a pair of oppositely situated openings in the throat for ejecting air from a compartment through the throat without admitting air through the throat into the compartment.

20 A further object of the invention is to provide, in a ventilator, an open end outer casing, an open end casing forming a throat within the outer casing and having an opening in the opposite walls thereof, with an air passage between the walls of the casing and the walls of the throat, and 25 a mechanically operated vane or valve within the throat and coöperating with said wall openings.

25 Various other objects, advantages, and improved results are attainable in the practical application of the invention by reason of the construction and relative combination of the several parts, as will be hereinafter fully described.

30 In the accompanying drawings forming part of this application:

Figure 1 shows part of the top of a car in longitudinal section with ventilators applied thereto and partly broken away.

Fig. 2 is a central longitudinal sectional view of a ventilator showing the reverse position of the vane or valve in dotted lines.

Fig. 3 is a cross section taken on the plane indicated by the dotted line A—A Fig. 5.

Fig. 4 is a detail perspective view of the throat and casing partly broken away.

Fig. 5 is a perspective view of the vane or valve.

Fig. 6 is a front view, partly broken away, showing a pair of shutters in partly closed position.

Fig. 7 is a perspective view of a shutter.

Fig. 8 is a detail sectional view of an end bracket showing means for controlling the 60 slidable bar.

Fig. 9 is a detail perspective view showing the connection between the slidable bar and the valve lever.

Fig. 10 is a perspective view of a modification partly broken away.

Fig. 11 is a similar view of a further modification.

The same reference characters denote the same parts throughout the several views of the drawings.

70 Although the ventilator is shown applied to a passenger car transom, it is quite as applicable to freight or express cars, automobiles and other vehicles, and to various inclosures where it is desirable to exhaust foul or impure air, and the invention is also applicable to refrigerator cars, and to windows of buildings, as will be hereinafter more particularly explained.

The frame or holder 1, has air exhaust or 80 transom openings 2, and slots 3 through which the stems 4 project from the shutters 5, and the stems are provided with suitable heads 6, for sliding the shutters. Springs 7, or their equivalent, may be employed to 85 press against the inner face of the shutters for retaining them in closely fitting slidable position. The inner end corners of the shutters are cut out so as to form a stop shoulder 8, and the side edge of the shutters is cut 90 away at 9 for the purpose as will be herein-after explained.

A slidable bar 10, is hung from or adjacent to the transom, by means of a plurality of hangers 11 through which the bar extends, and a special end bracket 12 is provided for holding the bar 10 in various 95 slideable positions as desired. The end bracket comprises a hollow screw threaded post 13 projecting from and in communication with a slot 14 through which one end of the bar 10 slides, a hollow set screw 15 having a lock nut 16, and containing a spiral spring 17, and screwing into the post. The spring 17 cushions a ball 18 against the face of the 100 bar 10, and the latter is provided with seats

19, hereinafter referred to, into which the ball is forced for holding the bar as desired. This end of the bar has a depending hand lever 20, for operating the bar. The bar 10 is provided with set blocks 21 having a slotted flange 22, and the purpose of these blocks will hereinafter appear.

The more essential features of the invention will now be described in detail. The outer casing 23 has open ends, and an inner wall or base 23^a provided with an opening 24 central of the length of the casing, said opening being of the same size and fitting over the transom opening 2, where the casing is secured by screws 25, or other suitable means. The casing 23 contains an open end valve-casing 26 forming a throat and preferably of shorter length than the casing 23, but having the ends thereof extending beyond the ends of the opening 24. The side walls of the casing 26 are solid throughout but the wall of the throat casing 26 opposite the base wall of the casing 23 has an opening 27 opposite the openings 2 and 24, and preferably of greater length than said openings. The throat casing 26 is so fixed within the casing 23 as to form an air passage 28 between three walls of the casing 23 and three walls of the throat casing 26. The vane or air valve 29 is pivoted in and central of the throat by means of a crank shaft 30, having a lever 31 working in the slot of the block flange 22, and this block is adjusted on the bar 10 according to the swing or throw of the valve 29, and for the same reason the ball seats at the end of the bar 10, are accurately spaced apart. The valve 29 spans the openings 2 and 24, and is swung by the sliding movement of the bar so as to have one end of the valve engage the wall of the throat adjacent to the throat opening 27, while the other end of the valve is in engagement with the base wall adjacent to one end of the opening 24, as particularly shown in Fig. 2 of the drawings, where it will be observed that (the moving direction of a car being indicated by the arrow —a) the position of the valve is such as to shut off the passage of air through the forward end of the throat and through the openings 27, 24 and 2 into the car, but the outside air currents pass over the valve and through the passage 28, and through the opposite end of the casing, and thereby draw the air from the car or other compartment through the rear or open end of the throat. Obviously when a car is moving in the opposite direction the position of the valve 29 is reversed as shown in dotted lines Fig. 2. The side edges and ends of the valve are provided with felt 32 or other suitable material for making an air-tight closure of the valve, and the wall of the throat adjacent

to the opening therein is also provided with similar material 32^a.

A plurality or chain of valves for each side of a car, in such numbers as desired or as occasion may demand, may be housed as hereinbefore described, and connected respectively with an operating bar 10, for each side of a car.

The shutters 5 are stopped in closing movement by the shoulders 8 striking a projection 33 of the base wall central of the openings 2 and 24, so that one or both shutters may be partially or entirely closed. The cut outs 9 of the shutters allow free operation of the crank lever, with one or the other of the shutters in closed position, or with both shutters partially closed. The shutters, of course, are operated to vary the exhaust ventilation and to close the same entirely. The openings 2 are covered by gauze netting 2^a.

Referring to the modification shown in Fig. 10, the casing 34, and throat 35 are practically the same as those hereinbefore described, and having air passages 36 36^a, but the valve 37 is straight and of sufficient length to span the throat 36^a, and the elongated opening 38, in a holder 39, which is adapted to be set in desired position for ventilation, and the valve is operated by a lever 37^a. This ventilator may or may not have slidable shutters applied thereto, and is applicable to a window or an automobile.

Referring to the modification shown in Fig. 11, the casing 40 is the same as those hereinbefore described. The throat 41 has only one open end, and the other end thereof is branched from the base plate 42 of the casing so as to close this end of the throat, and the base plate 42 is provided with an exhaust opening opposite an opening 44 in the holder 45. A single shutter 46 is slidably contained between the holder and the base plate.

It will be observed that no back draft or air current is permitted to enter a car or other compartment through these ventilators, that the ventilators may be applied wherever they may be found adaptable, and that the valve controlling device is such as to prevent valve movement or operation by air pressure.

We do not confine ourselves to any particular number of assembled ventilators, to any particular size or material in the manufacture thereof, nor to the particular position of the slidable bar, and we do not limit ourselves in the practical application of the invention, but reserve the right to make such changes and variations therein and in the application thereof as may come within the scope of the appended claims.

Having thus described our invention what

we claim as new and desire to secure by Letters Patent is:—

1. An ejector ventilator comprising a pair of open end casings secured together one within the other and affording an air channel between the walls of the casings and within the outer casing, the inner wall of the outer casing having an air opening in communication with the inner casing, the outer wall of the inner casing having an air opening in communication with said channel, a valve pivoted in the inner casing and closing communication between said openings, and means for operating the valve to alternately open and close communication between the ends of the casings and said openings.
2. An ejector ventilator comprising a pair of casings one within the other and having walls spaced apart, the inner wall of the outer casing having an air opening, the outer wall of the inner casing having an air opening opposite the opening in the outer casing and adjacent to a solid wall of the outer casing, a valve in the inner casing and closing communication between said openings, and means for operating the valve to alternately open and close communication between the ends of the casings and the openings.
3. An ejector ventilator comprising an outer casing having an air opening in the inner wall thereof, a casing fixed to said wall within the outer casing and having side walls flush with the sides of said opening, the outer wall of the inner casing having an air opening opposite the opening in the outer casing, a valve swingable in the inner casing and closing communication between said openings, and means for operat-

ing the valve to alternately open and close communication between the ends of the casings and said openings.

4. In an ejector ventilator, an open end outer casing having an air opening through the inner wall thereof, an open end casing contained within the outer casing and having an air opening through the outer wall thereof, said casings forming an air channel within the outer casing between the walls of the casings, a valve within the inner casing and closing communication between said openings, and means for operating the valve to alternately open and close communication between the ends of the casings and said openings.

5. In an ejector ventilator, an outer casing having an air opening in the inner wall thereof, a casing contained in the outer casing and having side walls fixed to said inner wall, the outer wall of the inner casing having an air opening opposite the opening in the outer casing, the inner casing terminating in open ends between said opening in the outer casing and the ends of the outer casing, a valve in the inner casing and closing communication between said openings, and means for operating the valve to alternately open and close communication between the ends of the casings and said openings.

In witness whereof we hereunto set our hands in the presence of two witnesses.

JACOB W. GERKE.
EDWARD J. BRAISTED.
EDMOND T. KELLEHER.
